UNITED STATES PATENT OFFICE

WILLIAM J. RAFTEY, OF ULSTER PARK, NEW YORK

SMOKER'S APPLIANCE

Application filed February 6, 1931. Serial No. 513,985.

This invention relates to smoker's appliance and has more particular reference to a smoking tube or a so called cigar or cigarette ash retainer, the object of the present invention being to provide a device of the character above mentioned, that is capable of ready application to a cigarette holder, the device being further adapted to accommodate the lit cigarette to prevent hot ashes from the cigarette falling on to a table or like support, thus providing a safety appliance as a guard against possible fire as often results from carelessness.

Other objects and advantages of the invention, and the nature of the invention will be best understood from a study of the following description, taken in connection with the accompanying drawings wherein:

Figure 1 is a side elevational view of the device, the same being shown as applied to a cigarette holder.

Figure 2 is a longitudinal sectional view therethrough.

Figure 3 is a transverse sectional view taken substantially on the line 3—3 of Figure 1.

Figure 4 is a plan view of a closure cap.

Figure 5 is a perspective view of a shield.

Figure 6 is a similar view of a perforated tube.

Figure 7 is a perspective view of an asbestos ring.

With reference more in detail to the drawings it will be seen that 5 designates a conventional type of cigarette holder, or mouth piece while 6 designates a cigarette one end of which is suitably arranged in the proper end of the holder or mouth piece 5. The cigarette is herein shown as being lit.

The invention per se consists of an elongated perforated tube 7 open at each end. The tube 7 is adapted to accommodate therein the cigarette 6, and said tube is adapted to accommodate in one end thereof the cigarette supporting end of the mouth piece or holder 5.

Disposed circumjacent about the perforated tube 7, in relatively spaced relation are rings 8, the same being formed of asbestos material.

Disposed circumjacent the tube 7, and spaced therefrom through the medium of the rings 8 is a cylindrical shield, the same comprising end sleeves 9 connected by an annular series of circumferentially spaced strips 10. 55 The said shield may be formed of any suitable material, and is substantially of a length corresponding to the length of the perforated tube 7.

For closing that end of the tube 7 farthest 60 remote from the mouth piece 5, is a perforated cap 11, the same being threaded for threaded engagement with an end sleeve 9 as clearly suggested in Figure 2.

When the tube, shield, and cap 7 arranged 65 as illustrated and specifically described herein, is properly associated with the mouth piece 5, it will be apparent that the appliance will in no wise interfere with the smoking of the cigarette or cigar as the case may be dependent upon the type of holder 5, and that further the device will act as a receptacle for receiving the ashes as they fall from the burning end of the cigarette thus preventing the ashes from scattering, and in the event 70 the cigarette or cigar, with my appliance associated with the holder of the cigar or cigarette, be placed on a table the possibility of fire is eliminated since the hot ashes will be prevented from coming into contact with the 75 cover of the table or with any other inflammable object or material.

Further, the asbestos rings 8 serving to space the shield from the tube 7 will prevent the shield from becoming too hot as to be 80 touched by the hand.

The operation of the device will be entirely clear from the above description without further explanation, and it is to be understood, that the invention is susceptible of 85 changes, modifications and improvements coming within the scope of the appended claim.

Having thus described my invention, what I claim as new is:

A smoker's appliance including in combination a casing for accommodating a cigarette projecting from one end of a cigarette holder, said casing comprising inner and outer concentric tubes of equal length, the 100

inner tube being perforated and the outer tube being provided with a circular series of relatively spaced slots elongated longitudinally, said inner tube at one end thereof adapted to receive one end of the cigarette holder, a cap threadedly engaged with the outer tube remote from the first named end of the inner tube, and longitudinally spaced asbestos rings circumjacent the inner tube.

10 In testimony whereof I affix my signature.
WILLIAM J. RAFTEY.
